UNITED STATES PATENT OFFICE.

CHARLES L. GOODRUM, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,334,300.

Specification of Letters Patent. Patented Mar. 23, 1920.

Application filed September 11, 1916. Serial No. 119,506.

To all whom it may concern:

Be it known that I, CHARLES LANE GOODRUM, a citizen of the United States, residing at Brooklyn, in the county of Kings and State of New York, have invented certain new and useful Improvements in Telephone-Exchange Systems, of which the following is a full, clear, concise, and exact description.

This invention relates to a class of service indicating arrangement, which may be applied to automatic or semi-automatic systems.

The main feature of this invention resides in associating characteristic tone generators with the test circuits of the subscribers' lines, so that these tones are inductively connected to the operator's position upon the extension of a calling line to that position.

The other features of the invention will be specifically pointed out in the following detailed description and claims.

Referring to the drawings, Figures 1 and 2, with Fig. 1 placed at the left of Fig. 2, diagrammatically represent a telephone system embodying the present invention. The portion of the diagram at the left of the dotted line in Fig. 1 represents all the apparatus individual to one subscriber's line and a portion of the apparatus individual to another subscriber's line in the same group; the portion of the diagram included between the dotted lines of Figs. 1 and 2 represents a line finder and its associated circuits; that portion of the drawings at the right of the dotted line in Fig. 2 shows a first selector and an operators' telephone set with its connecting plug and jack.

The invention herein disclosed is devised to transmit a characteristic signal or tone from the calling line to the operator's position. By this arrangement, the operator is informed of the class of service to which the calling subscriber is entitled.

The invention will be best understood by a detailed description of the operations involved in interconnecting a substation with the operators' position.

When the subscriber at substation 110 removes his receiver, a circuit is closed for the line relay 116, said circuit leading over the line circuit conductors 111 and 112, and through the telephone set of substation 110. This relay thereupon closes a circuit for relay *c'* to start a finder searching for this calling line. This circuit leads from the

free pole of battery, through the left-hand winding of relay 116, left-hand armature and back contact of the cut-off relay 120, conductor 121, contacts 117, 118, conductor *d'*, left-hand armature and back contact of relay *a'*, conductor 134, relay *c'* to ground. Relay *c'* thereupon locks itself up in series with the line relay 116 in a circuit leading through its left-hand armature and front contact, said circuit being independent of relay *a'*. Relay *c'*, at its right-hand armature and front contact, closes a circuit for the escapement magnet 217, to move the steering switch of the line finder into position 2, to begin the upward movement of the brush rod to cause the set of wipers of this line group to test for the calling line, assuming that the line finder normally associated with the starter wire 130 is not in use. Under such assumption, an arm 214 of the finder brush rod is in contact with a metallic segment 265, individual to this line group. This circuit is as follows: free pole of battery, magnet 205 (Fig. 2), conductor 212, magnet 217, conductor 218, arm 216, conductor 215, arm 214, segment 265, conductors 130, 127, right-hand armature and front contact of relay *c'* to ground. The magnet 205 is so adjusted and the circuit conditions are such, that it does not operate when this circuit is closed. The magnet 217, upon its energization, moves the steering switch to position 2, in which position the circuit for the said magnet 217 is maintained closed. This circuit may be traced as follows: free pole of battery, magnet 205, conductor 212, magnet 217, conductor 218, arm 216, now in its second position, conductor 287, conductors 202, 201, arm 200, conductor 129, right-hand armature and front contact of relay *b'*, conductors 128, 127, right-hand armature and front contact of relay *c'* to ground. The relay *b'* was energized upon the energization of relay *c'*. This relay is made slow-acting for a purpose set forth later.

The arm 210 of the steering switch in its second position closes a circuit for magnet 207, which, by interrupting its own circuit, raises the brush rod, during which movement the set of brushes wipes over the group containing the calling line. This circuit is as follows: free pole of the battery, secondary magnet 207, conductor 219, arm 210 and its second contact, conductors 209, 110

208, armature and back contact of magnet 207, conductors 268, 266, right armature and front contact of magnet 217, conductor 267, conductor 204, armature and back contact of release magnet 203, conductors 202, 201, arm 200, conductor 129, right-hand armature and front contact of relay b' , conductors 128, 127, right-hand armature and front contact of relay c' to ground. When 10 the brushes 221, 222 and 223 arrive upon the terminals 224, 225 and 226, representing the line of the subscriber initiating the call, the cut-off relay 120 of such line is energized over the following circuit: free 15 pole of the battery, relay 120, conductor 114, terminal 226, brush 223, conductor 113, contacts 228, 270 of magnet 217, conductor 271, resistance 272, conductor 201, arm 200, conductor 129, right-hand armature and 20 front contact of relay b' , conductors 128, 127, right-hand armature and contact of relay c' to ground. Cut-off relay 120, at its left-hand armature, opens the circuit of relay c' , which, in deenergizing, opens the 25 circuit of driving magnet 207. The finder is thus brought to rest upon the calling line terminals and is held there by holding means, not shown. When the cut-off relay 120 operates and deenergizes the relay c' , 30 the escapement magnet 217 also is deenergized, whereupon the steering switch moves to its third position. The closure of contacts 228, 229 of magnet 217 puts ground on the multiple test terminals of this line, 35 whereby connection cannot be made to it by a connector.

In the third position, the arms 232 and 233 of the steering switch connect the line conductors 111, 112 through to the line relay 234 of a selector. It will, of course, be understood that the operations involved in connecting the calling line with a connecting circuit just traced, take but a short interval of time. The line relay 234, at its 40 armature and front contact, closes a circuit for a slow-acting relay 235. The subscriber will now operate his sender. The relay 234 is adjusted to respond to each interruption of the line circuit, but the relay 235 is arranged to remain energized during such 45 interruptions. Each time the armature of the relay 234 closes its back contact, an impulse is given to a rotary driving magnet 236 to cause the brush rod of the first selector to be rotated, to position the proper set of brushes below a group of trunks terminating in operators' positions serving the desired group of subscribers. This circuit is as follows: free pole of battery, magnet 50 236, conductor 269, contact 237, which is closed as long as the brush rod is in its normal longitudinal position, conductors 238, 239, armature and front contact of slow-acting relay 235, armature and back contact 55 of relay 234 to ground. At the end of this

series of impulses, a relatively long interruption of the line circuit occurs, which causes the slow-acting relays 235 and 240 to become deenergized. It will be noted that relay 240 was energized upon the first 70 deenergization of relay 234 by a circuit leading through the armature and front contact of slow relay 235. The relay 240, at its front contact, closed a circuit for the escapement magnet 241 of the steering 75 switch of the selector, which, however, did not permit the steering switch to move. When the relay 240 is deenergized, it opens the circuit of escapement magnet 241. This permits the steering switch to move to its 80 second position to cause the set of brushes 246, 247, 248, which has thus been positioned, to hunt over the group of trunks for an idle trunk.

As soon as the steering switch arrives in 85 its second position, a circuit is closed for the vertical driving magnet 242 of the selector. This circuit may be traced as follows: free pole of battery, magnet 242 and its armature and back contact, steering 90 switch arm 243 and its second contact, conductor 244, conductor 245, armature and front contact of relay 234 to ground. The magnet 242 thereupon makes and breaks its own circuit, thus causing the brushes 95 246, 247 and 248 to wipe over the fixed contacts 249, 250 and 251. An idle trunk is represented by ground on the test contact 251 thereof. Therefore, when the test brush 248 reaches the contact 251 of an idle trunk, 100 a circuit is closed from the free pole of battery, escapement magnet 241, arm 252 and its second contact, conductors 253, 254, brush 248, test contact 251, conductor 255, contact 275, back contact and armature of 105 relay 271 to ground.

The escapement magnet is thereupon energized and moves the side switch to its third position. Relay 271 is then energized over a circuit which may be traced from 110 grounded battery, relay 271, jack contact 296, trunk conductor contact 250, brush 247, wiper 257 in its third position, lower side of the line, wiper 233 in its third position, brush 225, conductor 112, telephone apparatus 110, over the upper side of the line, through conductor 111, brush 221, wiper 232 in its third position, wiper 256 in its third position, brush 246, contact 249, trunk conductor contact 295 of the jack to ground. 115 When relay 271 is energized, a circuit is completed for lamp 299, from grounded battery, lamp 299, front contact and armature of relay 271 to ground.

When the lamp is lighted, the operator 120 responds by inserting a plug into the jack and on pressing listening key 276 will be connected with the calling party's apparatus. There are associated with several 125 subscribers' lines which may be connected 130

to the operator's position, characteristic tone generators herein indicated at 136 and 137. These tone generators indicate to the operator the class of service to which the calling subscriber is entitled. The characteristic tone generator associated with substation 110 is inductively connected to the operator's position over the following circuit: from grounded battery, secondary 10 winding of the induction coil 135, cut-off relay 120, conductor 114, contact 226, brush 223, conductor 113, contacts 228 and 229, conductor 230, left-hand armature and back contact of relay 203, and primary 15 winding of the induction coil 291 to ground. The interrupter at 136, by means of the primary winding of the coil, induces an alternating current in the circuit just described. The primary winding of coil 291 20 induces an alternating current in the secondary winding of this coil, which is in a circuit which may be traced from grounded battery, secondary winding of coil 291, release magnet 261, off-normal contact 260, conductor 259, wiper 258 in its third position, conductor 254, brush 248, contact 251, conductor 255, sleeve 294 of the jack, sleeve 293 of the plug, conductor 290, listening key 276, a winding of the induction coil of the operator's head set, condenser 298, to ground.

At the termination of the conversation, the operator removes the plug from the jack, which completes a circuit for restoring the switches to their normal position. This 35 circuit may be traced from free pole of battery, release magnet 261 of the selector, off-normal contact 260, conductor 259, wiper 258 in its third position, conductor 254, brush 248, contact 251, conductor 255, contact 275, armature and back contact of relay 271 to ground. A circuit in parallel with the last named circuit serves to release the finder switch. This circuit leads from free pole of battery, release magnet 203, finder 40 off-normal contact 262, conductor 263, right-hand armature and back contact of relay a' , conductor 264, conductor 281, conductor 259, wiper 258 and its third contact, conductor 254, brush 248, contact 251, conductor 255, contact 275, armature and back contact of relay 271, to ground.

The numerals 131 and 132 designate respectively the line relay and cut-off relay of another subscriber's line terminating at the finder switch. The tone generator 137 associated with this line is of different frequency from the tone generator shown in 55 136, by which the operator is able to distinguish between the various calling lines to which she may be connected.

It should be noted in connection with this system that the characteristic tone is inductively connected to the operator's position over a circuit in addition to, and independent of, the talking conductors connect-

ing any substation of the group served, with the operator's position.

Obviously, the invention is not limited to the specific embodiment herein shown and described, but is capable of many variations 70 and applications without departing from its spirit and scope.

What is claimed is:

1. In a telephone system, an operator's position, incoming line circuits, a trunk circuit leading to said position, means for interconnecting any incoming line circuit with said trunk circuit, a characteristic tone generator associated with said incoming line circuits, and a circuit independent of the talking conductors of said trunk circuit and incoming line circuits for inductively connecting said generator to said operator's position. 75

2. In a telephone system, an operator's position, incoming line circuits, a trunk circuit for interconnecting said operator's position with any incoming circuit, characteristic tone generators associated with said incoming line circuits, and another circuit independent of the talking conductors of said 80 trunk circuit for inductively connecting one of said generators to said operator's position. 90

3. In a telephone system, an operator's 95 position, incoming line circuits, a trunk circuit, means for associating said position with one end, and means for associating any incoming line circuit with the other end of said trunk circuit, a test circuit associated 100 with said last mentioned means, characteristic tone generators associated with said incoming circuits, and another circuit independent of the talking conductor of said trunk circuit but including a portion of said 105 test circuit for inductively connecting said generators to an operator's position.

4. In a telephone system, an operator's position, incoming line circuits, a trunk circuit leading to said operator's position, means 110 for interconnecting any incoming line with said trunk circuit, release mechanism for said interconnecting means, a release circuit for controlling said mechanism, a characteristic tone generator associated with 115 said incoming line circuits, and a circuit independent of the talking conductor of said trunk circuit but including a portion of said release circuit for inductively connecting said generator to the operator's position. 120

5. In a telephone system, an operator's position, incoming line circuits and a trunk circuit having talking conductors leading to said operator's position, a switch for interconnecting any incoming line circuit 125 with said trunk circuit, operating means for said switch, a test circuit associated with said switch, release means for said operating means, a release circuit for controlling said release means, a character- 130

istic tone generator associated with said incoming line circuits, and a circuit independent of the talking conductors of said trunk circuit but including portions of said test and release circuits for inductively connecting said generator to said operator's position.

6. In a telephone system, an operator's position, incoming line circuits and a trunk circuit having talking conductors leading to said position, a switch for interconnecting any incoming line circuit with said trunk circuit, means for operating said switch, release mechanism for restoring said switch to normal position, a test circuit associated with said switch and controlled at one point by said release mechanism, a characteristic tone generator associated with some of said incoming lines, and a circuit independent of the talking conductors of said trunk circuit but including a portion of said test circuit for inductively connecting said generator to said operator's position.

7. In a telephone system, an operator's position, incoming line circuits and a trunk circuit leading to said position, a switch for interconnecting any incoming line circuit with said trunk circuit, means for operating said switch, an escapement magnet for controlling said operating means, release mechanism for restoring said switch to normal position, operating circuits for controlling said escapement and release magnets, a test circuit associated with said switch and controlled at one point by said escape magnet and at another by said release mechanism, a characteristic tone generator associated with said incoming lines, and a circuit including a portion of said test circuit for inductively connecting said tone generator to the operator's position.

8. In a telephone system, an operator's position, incoming line circuits, means including two automatic switches for extending any of said incoming line circuits to said operator's position, a test circuit at one of said switches and a release circuit at the other switch arranged to be inductively connected together, a characteristic tone generator associated with certain of said incoming line circuits, and a circuit including portions of said test circuit and said release circuit for connecting said tone generator to said operator's position.

55. 9. In a telephone system, incoming line circuits, an operator's position, means including two automatic switches for interconnecting any incoming line circuit to said operator's position, a test circuit associated with each of said switches, a tone generator associated with certain of said incoming line circuits, and means including portions

of said test conductors for connecting said generator to said operator's position.

10. In a telephone system, incoming line circuits, an operator's position, means including two automatic switches for interconnecting any incoming line circuit to said operator's position, a test circuit associated with each of said switches, a tone generator associated with certain of said incoming line circuits, and means including portions of said test conductors for inductively connecting said generator to said operator's position.

75 11. In a telephone system, incoming line circuits, an operator's position, trunk lines terminating in jacks at said position, means including automatic switches for extending any incoming line circuit to any trunk line, a tone generator associated with certain of said incoming lines, means independent of the talking conductors of said trunk lines for connecting said tone generator to any of said jacks, and means coöperating with said jacks for detecting tones.

12. In a telephone system, incoming line circuits, an operator's position, trunk lines terminating in jacks at said position, means including automatic switches for extending any incoming line circuit to any trunk line, a tone generator associated with certain of said incoming lines, means independent of the talking conductors of said trunk lines for inductively connecting said tone generator to any of said jacks, and means coöperating with said jacks for detecting tones.

95 13. In a telephone system, incoming line circuits, an operator's position, trunk lines terminating in jacks at said operator's position, an operator's telephone set connectible to any jack, means for interconnecting any incoming line with any trunk line, a tone generator associated with certain of said incoming lines, and means independent of the talking conductors of said trunk for inductively connecting said generator to said operator's telephone set.

110 14. In a telephone system, incoming line circuits, an operator's position, trunk lines terminating in jacks at said operator's position, an operator's telephone set connectible to any jack, means for interconnecting any incoming line with any trunk line, a tone generator associated with certain of said incoming lines, and means independent of the talking conductors of said trunks for inductively connecting said generator to the sleeve conductor of said jacks.

115 In witness whereof, I hereunto subscribe my name this 8th day of September A. D., 1916.

CHARLES L. GOODRUM.
